UNITED STATES PATENT OFFICE.

HARRY WIARD, OF SYRACUSE, NEW YORK.

DESIGN FOR A SHOE FOR LANDSIDES FOR PLOWS.

SPECIFICATION forming part of Design No. 27,350, dated July 13, 1897.

Application filed May 28, 1897. Serial No. 638,638. Term of patent 14 years.

To all whom it may concern:

Be it known that I, HARRY WIARD, of Syracuse, in the county of Onondaga, in the State of New York, have invented and produced a new and original Design for a Steel Shoe for the Landside of a Plow, of which the following is a specification, reference being had to the accompanying drawings, showing a part thereof.

10 Figures 1, 2, and 3 are respectively top plan and side and end elevations of a shoe embodying my design.

15 The leading feature of my design consists in a steel shoe for the landside of a plow, which shoe when viewed in top plan and side elevation presents the appearance of a rectangle, and when viewed in end elevation presents the appearance of an L.

20 A is a steel shoe embodying my design. The outer, inner, top, and bottom faces $a'a'a^2a^3$ of the shoe A are substantially parallel with each other, and the end faces a^4a^4 of said shoe are

disposed at an angle to the former faces $a'a'$ a^2a^3 . The outer face a is formed at its upper portion with a lengthwise angular groove a^5 , 25 which causes the shoe A to present the appearance of an L when viewed in end elevation.

A shoe for the landside of a plow embodying my design presents a pleasing and characteristic appearance.

What I claim is—

The design for a shoe for the landside of a plow, substantially as herein shown and described.

In testimony whereof I have hereunto signed my name, in the presence of two attesting witnesses, at Syracuse, in the county of Onondaga, in the State of New York, this 1st day of May, 1897.

35 HARRY WIARD.
